Application August 3, 1948, Serial No. 147,910

Term of patent 14 years

(Cl. D34—15)

To all whom it may concern:

Be it known that I, Max Feintuch, a citizen of the United States, residing in New York, county and State of New York, have invented a new, original, and ornamental Design for a Bubble Producing Toy Figure, of which the following is a specification, reference being had to the accompanying drawing, forming a part thereof, wherein:

Fig. 1 is a side elevation of a bubble producing toy figure embodying my new design; and

Fig. 2 is a front elevation thereof.

I claim:

The ornamental design for a bubble producing toy figure, substantially as shown.

MAX FEINTUCH.
